FOREIGN PATENT DOCUMENTS

WO WO 2012071607 6/2012

Primary Examiner — Rosemary K Tarcza(74) *Attorney, Agent, or Firm* — Michael Best & Friedrich LLP(57) **CLAIM**

We claim the ornamental design for a radio charger, as shown and described.

DESCRIPTION

FIG. 1 is a perspective view of a radio charger according to an embodiment of the invention.

FIG. 2 is a front view of the radio charger shown in FIG. 1.

FIG. 3 is a rear view of the radio charger shown in FIG. 1.

FIG. 4 is a right side view of the radio charger shown in FIG. 1.

FIG. 5 is a left side view of the radio charger shown in FIG. 1. FIG. 6 is a top view of the radio charger shown in FIG. 1; and, FIG. 7 is a bottom view of the radio charger shown in FIG. 1. The elements shown in broken lines are included for the purpose of illustrating environment and form no part of the claimed design.
